DRIVE-IN THEATRE SPEAKER ENCLOSURE

Felix Buford Grigg, Gastonia, N. C.

Application March 19, 1956, Serial No. 40,678

Term of patent 14 years

(Cl. D26—14)

Fig. 1.

Fig. 2.

Figure 1 is a front perspective view of a drive-in theatre speaker enclosure, showing my new design; and

Figure 2 is a bottom plan view thereof.

I claim:

The ornamental design for a drive-in theatre speaker enclosure, as shown.
